UNITED STATES PATENT OFFICE.

ISAIAH CLEEVE GORDON COOPER, OF NEWCASTLE-UPON-TYNE, ENGLAND.

BATTEN MOLD PARTICULARLY FOR USE IN SHIPBUILDING.

Application filed February 17, 1920. Serial No. 359,312.

(GRANTED UNDER THE PROVISIONS OF THE ACT OF MARCH 3, 1921, 41 STAT. L., 1313.)

To all whom it may concern:

Be it known that I, ISAIAH CLEEVE GORDON COOPER, subject of the King of Great Britain, residing in Newcastle-upon-Tyne, 5 in the county of Northumberland and Kingdom of England, have invented a certain new and useful Improved Batten Mold Particularly for Use in Shipbuilding, for which I have filed application in England Feb. 13, 10 1919, Patent No. 139,864, March 18, 1920, and of which the following is a specification.

The present invention relates to an improved batten mold particularly suitable for use in shipbuilding.

15 According to the present invention, five or more flexible elements or battens are adjustably hinged together to form a batten mold, that is to say, each pair of elements is connected together by a hinge pivot adjustable along either of them, and is further connected similarly by hinge pivot elements to other battens.

20 The invention is more particularly described with reference to the accompanying drawings in which:—

25 Figure 1. is a diagrammatic view of a scribe board.

Figure 2. shows the development of lines given upon the scribe board.

30 Figure 3. shows a typical arrangement of battens forming a batten mold.

Figure 4. is a front elevation of the hinge pivot.

Figure 5. is a side view.

35 Figure 6. is a corresponding plan view. From the frame lines 1, 2, 3, 4, 5, and the plate edges AB and CD as usually represented for a ship upon the scribe board, the true lengths of the edges between each

40 frame are developed by known geometric means on parallel lines drawn at the spacing of the frames, that is to say a batten is laid along the line CEFGD and each point marked. Choosing any point on the batten as a fixed mark, set up the ordinates from this fixed mark constantly to a base 1. 2. 3. 4. 5, Fig. 2 and obtain the points *cefgd* and draw the curve through them.

45 Thus the true length of the line CD in Fig. 1. is shown at *cd* in Fig. 2. proportionately divided as to its parts intercepted between each frame at the points *e*, *f*, and *g*. The similar line for AB is *ab*.

A further line HK more or less curved

according to the curvature of the frame 55 lines 1. 2. 3. 4. 5, is drawn across the lines on the scribe board as shown in Fig. 1. with the ends within a few inches of the opposite corners of the plate represented by ABCD and completely within the boundaries of the 60 area ABCD. This line is expanded similar to CD and proportionately divided between the frames as shown at *hlmnk* in Fig. 2.

Battens or bars of some flexibility are laid around each frame line separately and 65 the intersections of the lines AB CD HK with the respective frame lines are marked, a batten or bar being used for each frame.

Further battens or bars are laid around the lines *ab cd hk* and each of the division 70 points are marked.

The whole of the battens are then assembled into a mold by the aid of the hinge shown in Fig. 4. (in one form). The upper elements X are adjustable to the marking 75 on the battens or bars measured from the frame lines and the bottom elements Y are adjustable to the marks on the battens or bars marked from the lines *ab cd* and *hk*.

The upper and lower elements are then 80 brought together, a pin W on one fitting into a socket V on the other in each case. The position of the pin of the one and the socket of the other are arranged so that the elements can rotate about the line of intersection of the edges of the battens or bars marked from the frames and the remaining bars. The upper and lower elements may be clipped together by pins Z or may be formed so as not to be parted provided that 90 free rotation is allowed.

The frame thus formed truly develops the shape of the surface represented by the scribe board. It may be further stiffened by the application of more elements and 95 bars in any positions but preferably to diagonal lines indicated at PQ and RS.

The batten mold assembled will be as Fig. 3. corresponding points being similarly lettered to the lines from which they were developed.

100 The hinge pivot elements consisting of the parts X and Y are adjustably clamped to the battens by means of set screws T. The number of hinged elements to be used follows the following law: where P is the number of pivots and N the number of batten then $P=3 (N-3)$.

I declare that what I claim:—

1. As an article of manufacture, a batten mold comprising in combination more than five battens, and one less hinge pivot elements than there are battens, means to clamp said hinge pivot elements adjustably on a pair of battens.
2. As an article of manufacture a batten mold comprising in combination a plurality of battens, a plurality of clamp members adapted to engage said battens adjustably along their length and having hinge pins thereon and a plurality of clamps adapted to engage said battens adjustably along their length and having sockets therein adapted to engage said pins.
- 15 3. As an article of manufacture, a batten

mold comprising in combination a plurality of battens, a plurality of clamp members adapted to engage said battens, adjustably 20 along their length and having hinge pins thereon and a plurality of clamps adapted to engage said battens adjustably along their length and having sockets therein adapted to engage said pins, and means to 25 lock said pins within said sockets.

In witness whereof, I have hereunto signed my name this 21st day of January, 1920, in the presence of two subscribing witnesses.

ISAIAH CLEEVE GORDON COOPER.
